US00D953614S

(12) **United States Design Patent** (10) Patent No.: **US D953,614 S**
(45) Date of Patent: **** May 31, 2022**

(54) **VAPORIZATION DEVICE**

(71) Applicant: **14TH ROUND INC.**, Los Angeles, CA (US)

(72) Inventor: **Thomas Fornarelli**, Chicago, IL (US)

(73) Assignee: **14TH ROUND INC.**, Los Angeles, CA (US)

(**) Term: **15 Years**

(21) Appl. No.: **29/720,326**

(22) Filed: **Jan. 11, 2020**

(51) LOC (13) Cl. **27-02**

(52) U.S. Cl.

USPC **D27/162**

(58) **Field of Classification Search**

(57) **CLAIM**

The ornamental design for a vaporization device, as shown and described.

DESCRIPTION

FIG. 1 is a top and front perspective view of a vaporization device showing my new design;

FIG. 2 is a top plan view of the design of FIG. 1;

FIG. 3 is a bottom plan view of the design of FIG. 1;

FIG. 4 is a left side elevational view, which is the same as a right side elevational view, of the design of FIG. 1;

and,

FIG. 5 is a front elevational view of the design of FIG. 1;

1 Claim, 3 Drawing Sheets
